DESIGN FOR A NEGLIGEE

Paige Salfeety, New York, N. Y.

Application July 9, 1942, Serial No. 107,449

Term of patent 3½ years

To all whom it may concern:

Be it known that I, Paige Salfeety, a subject of the King of Great Britain, residing in New York city, county of New York and State of New York, have invented a new, original, and ornamental Design for a Neglige, of which the following is a specification, reference being had to the accompanying drawing, forming part thereof, wherein:

I claim:

The ornamental design for a neglige, substantially as shown.

PAIGE SALFEETY.
